UNITED STATES PATENT OFFICE.

JAMES CLAYTON, OF COVENTRY, ENGLAND, ASSIGNOR TO THE VISCOSE COMPANY, OF MARCUS HOOK, PENNSYLVANIA, A CORPORATION OF PENNSYLVANIA.

APPARATUS EMPLOYED IN THE MANUFACTURE OF ARTIFICIAL SILK.

1,406,153.

Specification of Letters Patent. Patented Feb. 7, 1922.

Application filed September 5, 1919. Serial No. 321,992.

To all whom it may concern:

Be it known that I, JAMES CLAYTON, a subject of the King of Great Britain, residing at 12 Middlesborough Road, Coventry, 5 in the county of Warwick, England, have invented new and useful Improvements in Apparatus Employed in the Manufacture of Artificial Silk, of which the following is a specification.

10 My invention relates to machines employed in the manufacture of artificial silk, the said machines being of the kind operating in accordance with what is known as the Topham system wherein viscose, or the like, 15 is ejected from a nozzle into a setting bath and the threads formed are led under an immersion guide and up over a rotating drawing-roller guide, (known as a Godet) and then down through a thread-guide, or funnel, 20 into a rapidly rotating spinning-box in which the thread is coiled, the circumferential velocity of the rotating drawing-roller guide, or Godet, determining the rate of passage of the thread into the spinning-box. 25 I have found that the operation of initially passing, or threading, the thread through the thread-guide, or funnel, is much facilitated, especially in cases where it is desired to run the machine at a high 30 speed, if means be provided whereby the thread is, during the threading operation, subjected to the action of a drawing-roller guide, or Godet, which has, during such operation, a circumferential velocity slower 35 than that which the drawing-roller guide or Godet has when the thread is passing thereover on its way to the spinning-box during normal working of the machine. My invention is especially adapted, for instance, for 40 use in an apparatus in accordance with my invention the subject-matter of application, Serial No. 309509, A. D. 1919, for Letters Patent, in which apparatus, the ordinary drawing-roller guide, or Godet, can be run 45 so much more quickly than is done in ordinary machines that, without some provision according to my present invention, the full advantage of greater speed of output will not be practically obtainable owing to the 50 difficulty, of passing the thread through the thread guides, or funnels, when the drawing-roller guides, or Godets, are running at high speed, but my present invention is not limited, in its application, to apparatus of this

particular kind as it can be employed with 55 ordinary machines and enable these to be run at higher speed than hitherto.

According to my present invention I provide means whereby, when the threads are to be passed through the thread-guides, or funnels, the said threads can be passed over drawing-roller guides, or Godets, (all of which I will refer to as Godets) caused to rotate at the required slower circumferential speed. For this purpose I provide means 65 whereby the Godets have different species of rotation which I will describe, with reference to the accompanying drawings, promising that I do not limit myself to the precise details illustrated. 70

Figure 1 shows in vertical transverse section, and Figure 2 in side elevation, sufficient of the upper part of a machine to illustrate the application of my invention there- 75 to when I employ an additional Godet, upon a shaft separate from that of the ordinary Godet, over which the thread passes, through the thread-guide, or funnel and into the spinning-box when the machine is normally at work. Figure 3 shows a modifica- 80 tion wherein the additional Godet is connected to the ordinary Godet.

Like parts in all the figures are marked with the same reference numerals.

Referring first to Figures 1 and 2, the 85 spinning box is marked 4 and the thread-guide or funnel is marked 17. The ordinary Godet is marked C and is shown as being driven by a scroll-wheel n on the shaft N, engaging a scroll-wheel c², on the shaft c, of 90 the Godet C, which shaft c, is carried in the long tubular bearing c¹.

P, is an additional Godet, provided in accordance with my present invention. It is shown as being mounted on the shaft p 95 (carried in the long tubular bearing p¹) which has on it a scroll-wheel p² which engages with a scroll-wheel g, on a shaft Q, which is driven, by any suitable gear at a slower circumferential speed than that at 100 which the Godet C is driven. This can, for example, (assuming the Godets C and P to be, as shown, of equal diameter) be conveniently effected by reducing gear conveying motion from the shaft N to the shaft Q, or, if desired, the additional Godet P can be of 105 a diameter so much smaller than the diameter of the ordinary Godet C, that the God-

ets C and P can be driven at the same speed and have the desired difference in rate of circumferential velocity.

I do not limit myself to any particular relative speeds, but I may mention that satisfactory results are obtainable if the Godet P be driven at a circumferential velocity of 125 feet per minute and the Godet C at a velocity of 250 feet per minute.

10 When thread is to be passed through the thread-guide, or funnel 17, to the spinning-box 4, the said thread is passed over the slow moving Godet P, (as indicated at *x* in Figure 2) and can then be much more readily 15 threaded through the said guide, or funnel 17, than would be the case if the thread were passed over the quick-moving Godet C. After threading (which may be done in the usual way) is effected, the thread is transferred from the Godet P, to the Godet C, (as indicated at *y* in Figure 2) and coiling of the thread into the spinning-box proceeds.

The troughs *r* and channels *r*² are for carrying liquid which drips from the Godets, 25 into the space below and thence away to any suitable receptacle, or place.

In Figure 3 I have shown the additional Godet P formed in one with the ordinary Godet C, but of such smaller diameter that 30 the Godet P will have the required slower circumferential velocity.

What I claim is:—

1. In apparatus for spinning artificial silk, or the like, a spinning device and driven

35 roller guide means having different peripheral speeds, and over which a thread may be passed, alternatively at higher or lower speed, to the spinning device, the roller guide of lower peripheral speed affording means which facilitates the initial feed of 40 the thread to the spinning device.

2. In apparatus for spinning artificial silk, the combination of a spinning box, a 45 guide funnel for leading thread into the spinning box, and driven guide roller means having different peripheral speeds, and over which a thread may be passed to the funnel alternatively at higher or lower speed, the roller guide of lower peripheral speed affording means which facilitates the initial 50 feed of the thread to the spinning device.

3. In apparatus for spinning artificial silk, a spinning box, a pair of independent guide rollers, and means for driving the same at different peripheral speeds to afford 55 alternative feed means for leading a thread at higher or lower speed to the spinning box, the roller guide of lower peripheral speed affording means which facilitates the initial feed of the thread to the spinning 60 device.

In testimony whereof I have signed my name to this specification in the presence of two subscribing witnesses.

JAMES CLAYTON.

Witnesses:

ALBERT BROWN,
ANNIE L. WADE.
